Inventor:
Emil A. Christoph,
By Chase E. Lord,
Att'y.

UNITED STATES PATENT OFFICE.

EMIL A. CHRISTOPH, OF CHICAGO, ILLINOIS, ASSIGNOR TO KING LOCK COMPANY, OF CHICAGO, ILLINOIS, A CORPORATION OF ILLINOIS.

PADLOCK.

1,419,358.

Specification of Letters Patent. Patented June 13, 1922.

Application filed November 29, 1918. Serial No. 264,728.

To all whom it may concern:

Be it known that I, EMIL A. CHRISTOPH, a citizen of the United States, residing at Chicago, in the county of Cook and State of Illinois, have invented certain new and useful Improvements in Padlocks, of which the following is a full, clear, and exact specification.

My invention relates to an improvement in 10 padlocks.

The object of my invention is to simplify the construction of padlocks, while at the same time increasing their effectiveness by rendering them difficult to open by anyone 15 not having the proper key.

The invention consists, in one of its aspects, in the combination with the usual shackle and locking bolt of a padlock, of a rotatable plug controlling the operation of 20 said locking bolt and carrying a plurality of tumbler plates adapted to be moved transversely of and through the plug, the tumbler plates being constructed to fit on a special key so that when they are assembled in the 25 lock only the key so fitted is capable of aligning the tumblers to permit rotation of the plug.

Other novel features of my invention will be set forth in the following specification, 30 and more particularly defined in the claims.

In the accompanying drawings—

Figure 1 is a front elevation of the complete padlock;

Fig. 2 is an elevation of the interior of the 35 padlock with the front half of the casing and rotatable plug removed;

Fig. 3 is an elevation of the interior of the front half of the casing with the rotatable plug in position in its housing;

Fig. 4 is a sectional elevation of the padlock along the line 4—4 of Fig. 1;

Fig. 5 is a sectional plan view of the front half of the casing and plug housing along the line 5—5 of Fig. 3;

Fig. 6 is a sectional elevation of the rotatable plug and its key, both removed from the casing; and,

Fig. 7 is a section along the line 7—7 of Fig. 6.

Referring to the drawings, the casing of the padlock is made up of two half portions 10 and 11 held together by means of the shouldered rivets 12, 13, 14 and 15. Pivotally mounted on the rivet 12 is the shackle 16, having notches 17 and 18 at its oppo-

site ends. The locking bolt 19 is pivotally mounted on the shouldered rivet 14 and is provided with the lug 20, which engages the notch 18 to hold the shackle in locked position. The hooked end 21 of the locking bolt 60 is engaged by a projecting member 22 on the rotatable plug 23 in a manner to be herein-after described.

The single leaf spring 24, held in position around the shouldered rivet 15, tends to hold 65 the locking bolt in locking position in the notch 18, due to the engagement of the lower end of the spring with the lug 25 on the locking bolt. The spring also tends to throw the shackle into open position, shown in 70 dotted lines in Fig. 2, due to the engagement of its upper end with the notch 17.

The rotatable plug 23 is provided with a transverse opening 26 in which are located a plurality of thin flat plates or tumblers 27, 75 which are freely slideable on each other and in and through said transverse opening 26. Each of said tumblers is provided with a slot 28 capable of receiving a key 29, which enters the end of the plug 23 through the key slot 30. The rotatable plug 23 is mounted in the plug housing 31, fastened to the front half 10 of the casing. This housing has two diametrically opposite recesses 32 and 33 into which the tumblers project, as shown in 80 Fig. 4, when the key 29 is withdrawn from the lock. However, when the key is in operative position in the plug the tumblers are 85 all withdrawn from the recesses and aligned to prevent a true cylindrical surface, as 90 shown in Figs. 6 and 7, and permit rotation of the plug in its housing, the rotation being limited by the engagement of the lower end of the projecting member 22 with the lug 34 formed on the plug housing. The 95 rotatable plug is held in the casing by the engagement of shoulder 35 with the front half 10, the rear end of the plug projecting into the recess 36 in the rear half 11 of the casing.

In this form of lock the tumbler plates must be constructed and cut to fit the key instead of the key being cut to fit the tumblers, so that when the tumblers are assembled in the plug and placed in the casing only the 105 key on which the tumblers have been fitted will operate the lock.

Assuming the padlock closed and the parts in the position shown in Fig. 4, the lock may be opened by inserting the key 29 in the slot 110

30 in the plug 23, thereby causing the tumblers 27 to align themselves and withdraw from the recesses 32 and 33. The plug may then be rotated by means of the key and the 5 upper end of the projecting member 22 moved into engagement with the hooked end 21 of the locking bolt 19. A further rotary movement of the plug withdraws the lug 20 from the recess 18, and permits the spring 24 10 to throw the shackle 16 into the open position shown in dotted lines in Fig. 2.

Although I have shown and described the preferred embodiment of my invention, many modifications may be made without 15 departing from the spirit of the invention or its scope as set forth in the appended claims.

What I claim as my invention, and desire to secure by Letters Patent is:

20 1. In combination in a padlock, a casing, a shackle pivotally mounted in the casing, a spring normally tending to hold the shackle in open position, a locking bolt for said shackle, a rotatable plug in said casing 25 extending transversely of the sides thereof and having a vertical portion engaging said locking bolt to move it out of locking position when the plug is rotated, a housing for said plug extending inwardly from one side 30 of the casing and terminating short of the opposite side thereof, said housing having diametrically opposed recesses, and a plurality of tumblers in said plug normally projecting into said recesses to prevent the 35 rotation of said plug and capable of being aligned by means of a specially designed key to permit the rotation of the plug.

2. In combination in a padlock, a casing, a shackle pivotally mounted in the casing, 40 a spring normally tending to hold the shackle in open position, a locking bolt for said shackle, a rotatable plug extending transversely of said casing having a vertical portion engaging said locking bolt to move 45 it out of locking position when the plug is rotated, a housing for said plug carried by one side of the casing and extending at right angles thereto and of a length less than the distance between the sides of the casing, 50 said housing having diametrically opposed recesses, a plurality of tumblers in said plug normally projecting into said recesses to prevent the rotation of said plug and capable of being aligned by means of a 55 specially designed key to permit the rotation of the plug, and means on said housing for limiting the rotation of the plug when the bolt is operated to release the hasp.

3. In combination in a padlock, a casing, 60 a shackle, a locking bolt for the shackle, a rotatable plug controlling said locking bolt, a housing for said plug connected with one side of the casing and extending transversely thereof, said housing being fastened to receive locking tumblers and a 65

plurality of tumbler plates carried by and adapted to be moved transversely of and through said plug, said tumbler plates being constructed to fit on a special key so that when they are assembled in the lock the 70 key so fitted is capable of aligning the tumblers to permit rotation of the plug to operate the locking bolt.

4. In a padlock, a casing composed of suitable plates having side portions and 75 offset flanges adapted to abut to provide a space therebetween, a shackle pivotally mounted in the casing, means for normally holding the shackle in an open position, a locking bolt for the shackle, a rotatable locking plug extending transversely of the sides 80 of the casing, a housing for said plug projecting from one side of the casing and terminating short of the other and having pockets therein, tumblers carried by the said locking plug adapted to seat in said pockets to lock the plug, a keyway in the plug for receiving a key to release the tumblers to permit rotation of the plug, and a projecting part carried by the plug and located 85 at one side of the housing for engaging the locking bolt to release the shackle.

5. In a padlock, the combination with a casing composed of side plates having flanges adapted to abut, a shackle pivoted in 95 the casing, a locking bolt for holding said shackle in a locked position, a housing carried by one of said side plates and extending at right angles thereto, said housing having diametrically opposed recesses therein, a rotatable plug, tumblers carried by 100 said plug and adapted to enter said opposed recesses, said plug having a keyway to receive a key to raise said tumblers to permit a rotation of the plug, and means carried by the plug and cooperating with the locking bolt for releasing the shackle upon a rotation of the plug.

6. In combination, in a padlock, a casing, a hasp pivotally attached to the casing, a 110 swinging locking bolt for the hasp, a rotatable plug disposed within the casing having a radial extension adapted to engage said locking bolt to move it out of locking position when the plug is rotated, a locking housing for the plug having a lateral recess therein projecting inwardly from the side of the casing, and of a width less than the width of the plug, and plurality of tumblers normally projecting within said 120 recess to prevent rotation of the plug, said tumblers being adapted to be withdrawn from the recess when the plug is rotated, substantially as described.

7. In combination, in a padlock, a casing, 125 a hasp pivotally attached to the casing, a swinging locking bolt for the hasp, a rotatable plug disposed within the casing having a radial extension adapted to engage said locking bolt to move it out of locking posi- 130

tion when the plug is rotated, a locking housing for the plug having a lateral recess therein projecting inwardly from the side of the casing, and of a width less than the 5 width of the plug, and a plurality of tumblers normally projecting within said recess to prevent rotation of the plug, said tumblers being adapted to be withdrawn from

the recess when the plug is rotated, said housing being provided with an offset flange 10 contacting with the inner surface of one side of the casing, and rivets for securing said flange in position.

In testimony whereof I affix my signature.

EMIL A. CHRISTOPH.
